UNITED STATES PATENT OFFICE.

MERRELL W. BROWNING, OF JENNINGS, LOUISIANA.

DISK-PLOW SHARPENER.

1,238,252.

Specification of Letters Patent. Patented Aug. 28, 1917.

Application filed April 18, 1917. Serial No. 162,976.

To all whom it may concern:

Be it known that I, MERRELL W. BROWNING, a citizen of the United States, residing at Jennings, in the county of Jefferson Davis and State of Louisiana, have invented certain new and useful Improvements in Disk-Plow Sharpeners, of which the following is a specification.

This invention relates to disk plow sharpening devices and more particularly to a device or attachment which may be easily and quickly applied to disk plows or the like now in general use for the purpose of sharpening the edges of said disks.

One of the objects of the present invention is to provide a device or apparatus of the above general character having relatively few parts which will be inexpensive to manufacture. Another object is to provide a simple and practical device of the above general character capable of various adjustments in order to better coöperate with the disks at each side of the plow.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:—

Figure 1 is an enlarged plan view partly in section showing the complete device;

Fig. 2 is a side elevation, on a slightly reduced scale, of the device shown in Fig. 1;

Fig. 3 is a detail sectional view;

Fig. 4 is a detail elevational view of one side of the sharpening device; and

Fig. 5 is a detail elevational view showing the supporting frame for the sharpening device.

Referring now to the drawings in detail and more particularly to Fig. 2, 10 denotes one of the disks of an ordinary disk plow,

harrow, or the like, which implement usually comprises a series of disks mounted upon a shaft, 11 supported in suitable bearing members 12 at each end and carrying a platform 13 which may be loaded with stone for the purpose of increasing the weight. Upon the bearing members or uprights 12, as they will hereinafter be called, may be secured by means of adjustable clamps 14, a 60 pair of rods or shaft 11. Adjustable clamp devices 16 are mounted upon these rods 15 and carry therebetween a rod 17 parallel to the shaft 11. Upon this rod 17 is an adjusting clamp 18 from which is suspended the 70 main support 20 for the sharpening device.

It will thus be seen that this arrangement of parts permits the sharpening device to be moved along the rod 17 to a point adjacent any of the disks. Likewise the entire 75 rod 17 with the sharpening device may be moved backwardly or forwardly along the rods 15 in order to properly position the sharpening device with respect to the periphery of the disks 10. This arrangement 80 may also be bodily removed from one side of the plow and replaced upon the other side, for it is usually the case that the disks on one side are oppositely positioned with respect to those on the other. In other words, 85 the concave surfaces of the disks face outwardly with respect to the middle of the plow.

The sharpener supported from the member 20 comprises two pivotally connected 90 members 21 and 22, one of which carries an adjustable sharpening device or knife 23, while the other member 22 carries a pair of rollers 24, one above the other, as shown in Fig. 2, and an adjustable scraping plate 25. The first member 21 also carries a pivoted 95 arm 26 provided with a roller 27 at one end engaging the disk 10 and these parts may be adjusted laterally by means of slot connection 29. An arm 28 pivotally mounted at 100 30 upon the pivot of the two members 21 and 22 passes through this pivoted lever 26 and normally urges the same outwardly by means of spring 31 whereby the roller 20 always engages the disk 10. The scraping plate 25 is similarly urged toward the disk 10 by means of spring 32 mounted upon adjustable bolt 33. It is to be noted that the plate 25 is provided with a slot 34 adapted to 105 permit a relative in and out movement.

The degree of pressure with which the scraper 25 and knife 23 engages the disk

may be adjusted by means of the bolt 35 pivotally connected to one end of the member 21 and passing through the other member 22. The springs 36 and 37 at opposite sides thereof may be more or less compressed by means of a wing nut 38.

It is believed that the construction and method of use of the above device will be clear from the above description. It may

10 be stated, however, that the device as a whole, may be easily and quickly removed from the plow or applied thereto and shifted from one disk to the other, as desired, with a minimum amount of trouble. The degree 15 of pressure with which the knife engages the disk may be varied at will and the various adjustments permit the changing of the position of the knife with respect to the disk as well.

20 It is believed that the present invention which is of simple and practical construction, reliable and efficient in use and operation and inexpensive to manufacture, is adapted to accomplish, among others, all of 25 the objects and advantages herein set forth.

Without further analysis, the foregoing will so fully reveal the gist of this invention that others can by applying current knowledge readily adapt it for various applications without omitting certain features that, 30 from the standpoint of the prior art, fairly constitute essential characteristics of the generic or specific aspects of this invention, and therefore such adaptations should and 35 are intended to be comprehended within the meaning and range of equivalency of the following claims.

I claim:

1. In an apparatus of the character described, a pair of rods adapted to be adjustably clamped to a plow frame, a second rod parallel with the axis of the plow adjustably supported on said first mentioned rods and a sharpening device supported from 45 said second mentioned rod, said sharpening device comprising a pair of pivotally mounted arms, one of which carries a sharpening knife and the other a scraper, and means for urging said knife and scraper toward each 50 other.

2. In an apparatus of the character described, a pair of rods adapted to be adjustably clamped to a plow frame, a second rod parallel with the axis of the plow adjustably supported on said first mentioned rods 55

and a sharpening device supported from said second mentioned rod, said device comprising a pair of pivotally connected arms, an adjustable tension device acting between the ends of said arms to urge the opposite ends toward each other, the opposite ends each carrying a roller and a flat member adapted to coact respectively with opposite sides of the disk.

3. In a sharpening device for disk plows, 65 in combination, a central support, an arm carried thereby, a second arm pivotally connected with the first arm, a knife on one arm and a scraper on the other, and means for urging said knife and scraper into engagement with opposite sides of the disk of the plow.

4. In a sharpening device for disk plows, 75 in combination, a central support, an arm carried thereby, a second arm pivotally connected with the first arm, a knife on one arm and a scraper on the other, means for urging said knife and scraper into engagement with opposite sides of the disk of the plow, and means for adjusting the relative 80 position of the knife and scraper with respect to the arms upon which they are mounted.

5. In a sharpening device for disk plows, 85 in combination, a central support, an arm carried thereby, a second arm pivotally connected with the first arm, a knife on one arm and a scraper on the other, means for urging said knife and scraper into engagement with opposite sides of the disk of the 90 plow, and roller means carried by each arm engaging opposite sides of the disks.

6. In a sharpening device for disk plows, 95 in combination, a central support, an arm carried thereby, a second arm pivotally connected with the first arm, a knife on one arm and a scraper on the other, means for urging said knife and scraper into engagement with opposite sides of the disk of the plow, roller means carried by each arm engaging opposite sides of the disks, and 100 means for adjusting the relative position of the knife and scraper with respect to the arms upon which they are mounted.

In testimony whereof I affix my signature 105 in presence of two witnesses.

MERRELL W. BROWNING.

Witnesses:

OSCAR MALMBEG,
F. A. SMITH.
